UNITED STATES PATENT OFFICE.

EMIL HAEFELY, OF BASEL, SWITZERLAND, ASSIGNOR TO WESTINGHOUSE ELECTRIC AND MANUFACTURING COMPANY, A CORPORATION OF PENNSYLVANIA.

ELECTRICAL TRANSFORMER.

1,130,268.

Specification of Letters Patent.

Patented Mar. 2, 1915.

Application filed January 10, 1912. Serial No. 670,531.

To all whom it may concern:

Be it known that I, EMIL HAEFELY, a citizen of the Republic of Switzerland, and a resident of Basel, Switzerland, have invented a new and useful Improvement in Electrical Transformers, of which the following is a specification.

It has heretofore been usual in transformers to insulate the high tension and low tension windings from each other and from the iron core by means of sleeves composed of tough paper or cardboard, either alone or in combination with mica, or of mica only, these sleeves being disposed around the core and between the high and low tension windings. Such sleeves, and sleeves made of other tough insulating material, are however unsatisfactory in practice when exposed to high electromotive forces, such for instance as from over 20,000 to 25,000 volts, as they permit static discharges from the other coils of one of the branches of the high tension winding to creep over or beneath their surfaces, with the result that, the insulating material becoming carbonized, a path is sooner or later provided for the high tension current, over which a disruptive discharge or short circuit from the high tension to the low tension winding or the core may eventually take place. These remarks are equally applicable whether the surface of the sleeve be rough or smooth and whether it be cooled by air or by oil. In order as far as possible to prevent the formation of such a creepage path it has been proposed to allow the sleeve to project to a certain extent beyond the coils of the high tension winding or to arrange the parts of the sleeve at the side adjacent to the high tension winding in the form of steps, and thus as far as possible to prolong the path along which creeping may take place in accordance with the potential difference between the adjacent windings. This, however, necessitates a greater space between the winding and the core than is really requisite if only direct short-circuiting, not due to the existence of creeping surfaces, is taken into account, thus leading to a construction of transformer which, while more expensive, is by no means the most suitable. Moreover, the high potentials frequently employed in transformers for testing purposes and in conductors for long distance transmission involve the use of thick-walled insulating sleeves, which

however are subject to various defects. Although it is quite practicable, by means of suitable appliances, to manufacture stout but still absolutely homogeneous sleeves, it should not be forgotten that this can be effected only by subjecting the sleeves to very high temperatures and afterward allowing them to cool; and as such sleeves when in use in a transformer are subjected between idle running and full load to considerable variations of temperature, there is always the risk that on account of the alternate contraction and expansion of the material there may occur internal strains which may lead to a loosening of the structure of the sleeve. It consequently occasionally happens that current creeps from the high tension winding not over the outside of the sleeve, but first through several layers of insulating material, and then through the interior of the sleeve in the direction of the core. Thick-walled sleeves are moreover subject to the great defect of generating on their own account a fairly large amount of heat, due to dielectric hysteresis, which heat in the case of oil-transformers acts to increase the temperature of the oil.

Now this invention relates to an insulating sleeve which is especially suitable for oil-transformers of the core-type exposed to high electro-motive forces and by means of which both the risks due to the formation of a creeping surface or path and those due to the generation of heat by dielectric hysteresis are considerably diminished, if not entirely obviated. The sleeve is made throughout of insulating material, but it is not entirely homogeneous in the direction of its thickness, but is partially of hard and partially of soft texture. The hard layer imparts to the sleeve the necessary mechanical rigidity, while the soft layer, which consists of an absorbent or suction-producing material adapted to become completely saturated with oil, and yet to retain its softness, serves to effect the main insulating work of the sleeve, that is to say, it is subjected to the highest potentials at which brush or other static discharges might take place in the transformer.

The accompanying drawing illustrates several sleeves constructed in accordance with this invention, Figure 1 being a vertical section of a sleeve in its simplest form. Fig. 2 shows in vertical section a sleeve hav-

105

110

ing several different layers. Figs. 3 and 4 show respectively in vertical and horizontal sections a sleeve placed between the windings of an oil-transformer of the core-type, and 5 Figs. 5 and 6 are vertical sectional views of further modified forms of insulating barrier.

In all cases the form of cross section of the sleeves may be different from the circular form.

10 In all these examples, the inner layer *a* of the sleeve is hard and may consist of tough paper, either alone or in combination with mica. It is surrounded by a comparatively soft layer *b* of an absorbent substance, such, 15 for instance, as textile fabric, blotting paper, cellulose board or the like.

For covering the soft layer *b* and for protecting it against deformation and against the pressure of the high tension winding, 20 it is surrounded, as shown in Figs. 2, 3 and 4, by a comparatively thin, but hard and rigid layer *c* which may consist either of the same material as the layer *a* or of a band of cotton or the like.

25 A sleeve of the kind just described, after it has been rolled and shaped by suitable means, is immediately immersed in hot transformer oil until its soft layer has been saturated thereby. The latter operation 30 may also be carried out in a vacuum stove.

As Fig. 3 shows, the covering layer *c* may be cut away in the well-known manner at the top and bottom to about the extent to which it is intended that the sleeve should 35 project beyond the high tension winding of the transformer in order to prevent the formation of a creeping surface. The high tension winding is represented in this figure, as well as in Fig. 4, by the letter *h*, while 40 the low tension winding has the letter *n* and the core the letter *k*. The surface of the uncovered part of the layer *b* which projects beyond the winding *h* and which is saturated with oil, is in direct contact with the oil which surrounds the sleeve when in use 45 in the transformer, with the result that the circulation of the oil is promoted and consequently the heat is led away from the hard layer *a* in a most advantageous manner.

50 With any of the above described insulating barriers, it is substantially, if not entirely, impossible for heat to be generated in the barrier itself by dielectric hysteresis or otherwise, first on account of the soft and 55 sponge-like character of the layer *b* which is saturated continuously with oil, and secondly because the heat can be conducted away from the hard layer *a* of the sleeve more rapidly and effectually than would be the case if only its exterior and interior surfaces were in contact with the oil in the transformer.

By means of sleeves of the kind described 60 there can be obtained greater security 65 against the risk of creeping from the high

tension to the low tension winding or to the iron core than is obtainable by means of sleeves of the usual kind, while, should the same degree of security as can be obtained by means of ordinary sleeves, be considered sufficient, the dimensions and cost of the whole transformer may be considerably reduced.

The objects of the invention may also be fulfilled by a sleeve having the soft layer 75 within the hard one as shown in Fig. 5; or a soft layer may be arranged on both sides of the hard layer as shown in Fig. 6.

Having now particularly described and ascertained the nature of my said invention 80 and in what manner the same is to be performed, I declare that what I claim is:—

1. An insulating structure for electrical apparatus comprising a layer of hard rigid non-porous insulating material, a layer of 85 soft porous insulating material supported thereby, and an oil bath.

2. An insulating structure for electrical apparatus comprising a layer of rigid non-porous insulating material, a layer of absorbent insulating material supported thereby, and a bath of insulating fluid.

3. An insulating structure for electrical apparatus comprising a layer of insulating material that imparts rigidity to the barrier, a layer of absorbent insulating material, and an immersion bath of insulating fluid.

4. An insulating structure for electrical apparatus comprising a sleeve of insulating 100 material that imparts rigidity to the barrier, a sleeve of absorbent insulating material, and an immersion bath of insulating fluid.

5. An insulating structure for electrical 105 apparatus comprising an oil bath, a sleeve of insulating material that imparts rigidity to the barrier, and a sleeve of material that absorbs oil and thereby constitutes the principal insulating medium.

6. An insulating structure for electrical apparatus comprising an oil bath, two spaced layers of rigid non-porous insulating material, and a layer of absorbent insulating material between the aforesaid layers.

7. An insulating structure for electrical apparatus comprising an oil bath, two spaced layers of rigid insulating material, and a layer of absorbent insulating material between the aforesaid layers one of the rigid layers being shorter than the others.

8. In an electrical device, the combination with parts to be insulated from one another, of an interposed insulating structure comprising a layer of rigid insulating material, a layer of absorbent insulating material, and an oil bath.

9. In an electrical device, the combination with parts to be insulated from one another,

of an interposed insulating structure comprising two spaced layers of rigid insulating material, a layer of absorbent insulating material between the aforesaid layers, and

5 an immersion bath of oil.

10. In an electrical device, the combination with parts to be insulated from one another, of an interposed insulating structure comprising two spaced layers of rigid insulating material, a layer of absorbent in-

sulating material between the aforesaid layers, one of the rigid layers being shorter than the others, and an oil bath.

In testimony whereof I have signed my name to this specification in the presence of 15 two subscribing witnesses.

EMIL HAEFELY.
